LUGGAGE SEAM REINFORCED BY A
U-SHAPED PLASTIC STRIP HAVING A
T-SHAPED CROSS-SECTION

Leo Stein, Chicago, Ill.

Application September 3, 1948, Serial No. 47,719

1 Claim. (Cl. 190—54)

1

This invention relates to luggage reinforcement and more particularly to reinforcing edging for a case.

It is well known that in the handling of luggage the edging of the same takes a great deal of beating and as a result the wear and tear of the same is much greater than the other portions of the case. In addition the strains placed on the edges of the case occasion weakening of the seams so that unless they are protected they are apt to break open.

An object, therefore, of this invention is to provide an improved reinforced edging for cases such as luggage and the like.

Another object of this invention is to provide a predetermined frame like edging adapted to be readily incorporated in the seam of a case or piece of luggage by stitching.

A still further object of this invention is to provide a synthetic resilient preshaped edging for a luggage case which can be bodily incorporated in the seamed edge of the case during the assembly of the walls of the case together.

In accordance with the general features of this invention there is provided a protecting rail or strip of generally T-shape cross-section for disposition around joined margins of the walls of the case at a seam, the strip being made of synthetic thermoplastic material having its head portion beyond the seam and its stem flange portion embodied in the seam.

Another feature of the invention relates to the making of the reinforcing strip or rail in the form of a generally U-shaped frame with an inwardly projecting flange for fastening between adjoining edge portions of the case and embodiment in the ensuing seam.

Other objects and features of this invention will more fully appear from the following detail description taken in connection with the accompanying drawing which indicates an embodiment thereof and in which:

Figure 1 is a view of a luggage case to which my novel reinforcing edge has been applied;

Figure 2 is a fragmentary view of one of the corners of the edge with the outer wall of the case broken away to show the manner in which the stem flange of the reinforcing edging is embodied in the seam;

Figure 3 is a fragmentary cross-sectional view taken on substantially the line III—III of Figure 2 looking downwardly;

Figure 4 is a fragmentary view of a corner portion of my reinforcing T-shaped strip prior

2
to the bending of the same to form the corner; and

Figure 5 is a view similar to Figure 4 showing the condition of the reinforcing edge or strip after the same has been bent.

As shown on the drawings:

The reference character 10 designates generally a case to which my invention is applied and which case, in the embodiment selected for illustration, is shown in the form of a brief case. However, it is clear that my invention can be applied equally well to other shapes and forms of cases.

This case embodies two walls 11—11 which can be made of leather, synthetic leather, plastic, reinforcing cardboard and in fact any other type of sheeting such as is commonly used in cases. As is well known, the walls 11 are connected together by a connecting rod or so-called bellows gusset designated generally by the reference character 12. The adjoining marginal portions of each wall 11 and the gusset wall 12 are joined together by conventional seam fastening means at 13.

In accordance with the features of this invention it is the aim to embody in this seam a portion of my novel reinforcing edging or strip designated generally by the reference character 15. The strip 15, which is a very important part of my invention, is of a generally T-shaped cross-sectional shape and has the cross leg or head of the T, designated 16, exposed in reinforcing relation over the edges of the seamed marginal edge portions of the walls. The other leg or stem 17 of the strip and which corresponds to the vertical leg of a letter T is positioned in the seam 13 by being fastened in place between the adjoining parallel marginal portions of the two walls 11 and 12 by stitching 18 and 19, as shown in Figure 3.

The leg or flange 17 should be made sufficiently thin and of substantially uniform cross section throughout the length of the strip so that a stitching needle can readily penetrate the seam. Of course it is clear that this flange 17 could be pre-perforated but obviously it would be more economical to effect the perforating of the seam as shown in Figure 2 at the same time that the stitching is effected.

In order for my reinforcing edging or rail 15 to better withstand the wear and tear of the case and to protect the seam 13, I find it desirable to make this rail of a material which will give resiliency when the edge is subjected to forces normal to a plane containing the strip and yet will provide rigidity, particularly at corner portions of the U-shaped strip, when the strip is subjected to blows or forces acting along

lines parallel to said plane containing said U-shaped strip. It is desirable that the reinforcing and rigidifying strip hold its shape and not scuff when it is subject to impact blows.

I have obtained excellent results by making this edging of form sustaining synthetic plastic material which may be of any suitable type such, for example, as vinyl resins, ethyl cellulose and the like. Plastic seems to be ideally suited in view of its lightness and resilient bending qualities.

The T-shaped reinforcing edge strip 15 may be obtained in molded strip form as in Figure 4 and cut to a length suitable to go clear around a wall 11 from one side of the top to the other, as shown in Figure 1. In other words, the piece of cut strip should be bent into a generally U-shape before application to the case.

In order to readily effect bending and shaping of the strip in this U form, the corners may be relieved, as at 21, by notching, recessing or aperturing the same so as to get rid of excess material at the inner edge of the rail when it is bent from the form shown in Figure 4 to that shown in Figure 5. After the bending operation, the material where it is notched or recessed at 21 can be heated to seal and fuse the material together, thereby rendering continuous the flange or stem 17 even in the U-shaped form while maintaining the substantially uniform cross-section thereof desirable for facilitating stitching.

Upon the forming of this T or strip into the U-shaped form described above, it is then placed around a wall 11 and its leg or stem flange 17 is inserted between the margin of the wall 11 and the parallel margin of the gusset wall 12 after which it can be interlocked to these walls by the seam described above.

It is to be understood that in the event it is desired that the rail or edging strip go clear around a side of a case or piece of luggage, it would be in the form of a closed angular ring embodying the basic U-shape.

Also, the rail could be extruded, although it is contemplated, when the desired production is of sufficient quantity to warrant the expense, that it could be molded in the U or closed angular ring shape desired which would eliminate the operations shown in Figures 4 and 5.

I claim as my invention:

In an article of luggage having two walls, said walls having parallel marginal portions connected by a seam, a generally U-shaped reinforcing edge strip of form-sustaining thermoplastic material for disposition around said walls at said seam, said edge strip being of generally T-shape cross-section with the head portion of the T extending transversely in reinforcing relation over edges of the adjacent parallel marginal portions of the walls at said seam and with the stem of the T positioned between said parallel marginal portions, stitches securing said stem to said parallel marginal portions, said head portion and stem being integral and having a substantially uniform cross-section throughout the length of the strip whereby said stem can be secured by a continuous row of stitches, and said T-shaped cross-section providing resiliency in said U-shaped strip when said strip is subjected to forces normal to a plane containing said U-shaped strip, and providing rigidity, particularly at round corner portions of the U-shaped strip, when said strip is subjected to blows or forces acting along lines parallel to said plane containing said U-shaped strip.

LEO STEIN.
